UNITED STATES PATENT OFFICE

CHARLES W. STIFF, OF FOXBOROUGH, AND NATHANIEL C. BOUSLEY, OF SALEM, MASSACHUSETTS.

PHOTOGRAPHIC CAMERA.

SPECIFICATION forming part of Letters Patent No. 299,289, dated May 27, 1884.

Application filed August 27, 1883. (No model.)

To all whom it may concern:

Be it known that we, CHAS. W. STIFF, of Foxborough, in the county of Norfolk and State of Massachusetts, and NATHANIEL C. BOUSLEY, of Salem, in the county of Essex and State of Massachusetts, have invented certain new and useful Attachments for Photographic Cameras, of which the following, taken in connection with the accompanying drawings, is a specification.

Our invention relates to an attachment for photographic cameras, and has for its object the more efficient regulation of the time of exposure of the plate; and it consists in an apparatus for automatically closing the doors or slides of a camera at any predetermined time after the opening of the same, and mechanism of a novel construction and arrangement for regulating the working of the same, all as will be more readily understood by reference to the description of the drawings and the claims, to be hereinafter given.

In the drawings, Figure 1 represents a side elevation of our improved apparatus applied to a camera, but not in action. Fig. 2 represents an edge view of the door or slide operating mechanism. Fig. 3 represents a side elevation of our improved presser and timing mechanism as in action. Fig. 4 represents a plan of same. Figs. 5, 6, and 7 represent details, which will be more fully described further on in the specification.

A is a photographic-camera box, of the usual construction, provided with two doors, B B', which cover the inner end of the lens-tube C, and are firmly secured to the shafts a a', mounted in suitable bearings, b b, secured on either side of the tube C to the camera A.

To the upper ends of the shafts a a' are secured the rocker-arms e e', which are connected together by the connecting-rod d. To the lower end of the shaft a is secured a similar rocker-arm, to which is secured the rod f, mounted loosely in the guide f', and having at its other end a head or pad, f'', which, by means of the tension of the spring d', acting upon the rod d, is pressed firmly against and compresses the bulb D, which is made of rubber, of the usual construction, and is supported in place by the brackets g. The spring d' acts, also,

to hold firmly in place the doors B B' against the edge of the tube C when the apparatus is not in action. As shown in Fig. 2, the arm e is secured to the shaft a, so as to move through an angle of about ninety degrees above its center, while the arm e' rocks below its center, said arms being connected together by the rod d, thereby causing the shafts a a', with their respective doors, to oscillate in opposite directions simultaneously.

To the outer end of the bulb D is secured the rubber tube E, which has at its other end a larger bulb, F, which is of the usual construction. These bulbs D F and tube E are connected together, so as to be perfectly air-tight. By pressure upon the bulb F air is forced therefrom to the bulb D, inflating the same to the form shown in dotted lines in Fig. 1, thereby moving the rod f to the left, and operating the shaft a, and through rocker-arms e e' and rod d the shaft a', which opens the lids B B' and allows the plate to be exposed. This arrangement of rocker-arms and connecting-rod to operate the lids B B' in opposite directions is very simple and effectual, the advantage of which is obvious. The bulb F is placed between the frame G of the presser shown in Figs. 1, 3, and 4, and the lever H, which is pivoted at h to the brackets I I, which are firmly secured to the frame G. The tube E extends from the bulb F, between the uprights i i, and over the forked bracket j, to the bulb D. The spring J, inserted between the longer arm of the lever H and the frame G, tends to separate the two.

To the uprights i i is pivoted the nipper-lever i', which is provided at one end with the projections i' i''—one on either side of the bracket j and above the tube E in the fork of said bracket—and which is provided at its other end with the slot i''' into which projects the notched hook j', pivoted at its lower end to the bracket j'', and pressed against the outer end of the slot i''' by the spring i''.

To the upper side of the lever H is secured the clock-work frame K, which is provided with a shaft, k, about the lower end of which is coiled the spring k', fastened at one end to the shaft k and at the other to one of the legs k'' of the frame K. The shaft k has secured

also to it the ratchet-wheel k^3 , which has a pawl, k^4 , mounted upon a gear, k^5 , loosely fitted to the shaft k , so that it will not revolve when the spring is being wound; but as soon as the spring causes the shaft to take the opposite direction the teeth of the ratchet-wheel engage with the spring-actuated pawl k^4 and cause the gear to revolve with it, thereby revolving the pinion l , into which it meshes. 5 The pinion l is mounted on the shaft l' , which has secured to it the gear-wheel l'' , which meshes into the pinion m on the shaft m' and causes that to revolve together with the gear-wheel m'' , mounted on the same shaft there- 10 with, which in its turn meshes into and revolves the pinion n on the shaft n' , which also has secured to it the friction-disk n^2 and fan n^3 . The purpose of the fan n^3 is to steady the motion of the clock-work in a well-known manner. 15 Against the under surface of the friction-plate n^2 is pressed firmly one end of the lever o , pivoted at o' by the expansive force of the spring o^2 , thus operating as a brake and preventing the working of the gears when the 20 lever H is not depressed.

To the upper part of the frame K is secured, by suitable supports, the dial M , on which the finer graduations (shown in the drawings at Fig. 4) represent quarter-seconds, and through 25 which extends the shaft k , to the end of which are firmly secured, so as to revolve therewith, the pointer k^6 and milled head k^7 , by which the hand is set at any point desired. When the clock-work is not in action, the pointer 30 should be at zero-point. The ratchet-wheel k^3 should have as many teeth in a given angle as there are graduations in the same angle on the dial M , so that by moving the pointer three 35 points the pawl k^4 engages with the third tooth from that with which it was engaged when in 40 its normal position; and if the clock-work were allowed to run the ratchet would move said pawl, and with it the gear on which it is mounted, to its normal position, when the hand 45 or pointer would again be at zero-point.

To the upper surface of the frame K is secured a bracket, to which are pivoted a bent lever, p , and a spring-actuated dog, q , the latter of which enters a slot in the end of the lever o 50 farthest from the friction-disk n^2 , and is firmly pressed against the outer end of said slot by its attendant spring. The upper end of the bent lever p is in contact with the under side of the outer end of the lever o , while its lower 55 end extends below the upper part of the frame K .

To one side of the frame G is pivoted the notched lever s , which extends through a slot in the horizontal projection r of the bracket r' , 60 which is firmly secured to the shorter arm of the lever H . The spring s' serves to press the lever s against the outer edge of the slot in the bracket, so that the notch s^2 will the more readily engage therewith when in a position so to 65 do. The upper part of the lever is provided with a bent arm, s^3 , the object of which will

be more fully described. The frame G may be fastened to the camera-stand, if desired; or the presser may be used in both hands, like a lemon-squeezer. 70

When the operator is ready and desires the exposure to take place, he sets the pointer at a graduation equivalent to the time he wishes the plate exposed, which, as shown in the drawings, is seven seconds. He then simply presses the 75 longer arm of the lever H down as near to the frame G as possible, and then the apparatus will do the rest. By pressing down upon the longer arm of the lever H the bulb F is compressed, and the air contained therein forced 80 through the tube E into bulb D , inflating the same, as shown in dotted lines in Fig. 1, thereby causing the head f^2 and rod f to move forward, which rocks the rocker-arms e and e' and the shaft a , with its lid B , through an angle of 85 ninety degrees, and the arm e being connected by the rod d to the arm e' on the shaft a' , that also is moved, at the same time rocking the shaft, with the lid B' , through the same angle. To prevent the tension of the spring d' , acting 90 through the rocker-arms e and e' , shaft a , and rod f , from pressing any of the air back into the bulb F , the projection u is firmly secured to the lower surface of the shorter arm of the lever H , which projection, as it is raised with the shorter arm, comes into contact with the notched hook j' , disengaging it from the lever i' , and thus allowing the spring i^5 to press down the outer end of the lever i' , thereby bending the tube E over the forked bracket between the 95 projections i^2 and i^3 , thus preventing any air from returning (as shown in Fig. 5) and keeping the lids B and B' in the positions shown in dotted lines in Fig. 2 until the nippers i^2 and i^3 are withdrawn from the tube E . By the pressing down of the 100 longer arm of the lever H the horizontal projection of the bracket r' , secured to the shorter arm, is raised, so that it engages with notch s^2 , which is provided with a shoulder, on which the projection rests and holds the lever H in the position shown in Fig. 3. At the same time, by the depression of the longer arm of the lever H , the lower end of the bent lever p is brought 105 against the bent arm p' , firmly secured to one of the brackets I , thereby moving the lower end outwardly, and consequently the upper end inwardly, thus lifting the lever o so that the notched dog may engage therewith and prevent the other end of the lever o from coming in contact with the friction-disk n^2 , thereby allowing of the working of the gears. It 110 must be understood that the engagement of projection r with the notch s^2 of the lever s , the nipping of the tube E , and the starting of the clock-work all take place simultaneously. 115 At that point the pointer starts from the position in which it has been placed and steadily moves toward zero-point, at which point it stops, the arm v , secured to the shaft k , having come in contact with and disengaged 120 the dog q from the lever o , allowing the spring o^2 to press its end of the lever against the disk 125 n^2 from the lever o , allowing the spring o^2 to press its end of the lever against the disk 130

n^2 , stopping the mechanism. At the same time the arm w , also secured firmly to the shaft k , comes into contact with the bent arm s^3 of the lever s , disengaging the notch s^2 from the projection r of the bracket r' , thus allowing the lever H to regain its normal position, in order to do which it is necessary that the shorter arm should move downward in an arc about its pivot. During this downward movement of the short arm the plate x , secured thereto, comes into contact with one end of the lever i' , depressing the same so that it is engaged by and held by the notched hook j' , thereby raising the nippers i^2 i^3 from the tube E , thus allowing the air to come back from the bulb D to the bulb F , when the lids B B' are closed by the tension of the spring d . By the present use of the dry-plate process the interval of exposure should be very exact, which it is impossible to acquire by any of the present means, where the operator must be very skilled to expose his plate an exact second, while by our apparatus the plate may be exposed readily for any interval that may have been determined upon, even to a very small fraction of a second.

As shown in the drawings, the apparatus will expose the plate one-quarter second, as the shortest interval; but the plate may be exposed a much shorter space of time by replacing the ratchet-wheel k^3 with one having as many more teeth in a given angle, to give the required movement to the gear k^5 .

Any suitable expansive chambers may be used in place of the bulbs D and F without in any way altering the principles of our invention.

When it is desired to open the doors or lids B B' for the purpose of adjusting the camera, and to keep them open for an indefinite length of time, it is simply necessary to operate the presser G H , to compress the bulb F , as before described, but without previously adjusting the clock-work; or, in other words, allowing the pointer k^6 to remain at zero-point. The notched lever s will operate to keep the bulb F compressed and the nipper-lever i' will close the tube E , as before mentioned; but the clock-work will not operate, inasmuch as the arm v , mounted upon the shaft k , will remain in contact with the hook or dog q , which, being pressed backward by said arm v , will rest against the end of the slot in the lever o , through which said dog q projects, and thus form a stop to prevent the shaft k from revolving, even though the lever o be removed from contact with the friction-disk n^2 . When it is desired to again close the doors B B' , the operator will press upon the upper end of the lever s , so as to disengage it from the projection r , and the parts will then return to their normal position.

What we claim as new, and desire to secure by Letters Patent of the United States, is—

1. In combination with a photographic camera, a mechanism to be worked by the oper-

ator, and arranged and adapted to open the lids or shutters of the lens-tube, a device for automatically locking and retaining said lids or shutters in their open positions, and a timing mechanism arranged to be set in motion by the operation of the shutter-opening mechanism, and to release said locking device and permit the closing of said lids or shutters at the end of any predetermined interval of exposure.

2. A pneumatic device adapted to open the lids or shutters of a photographic camera, and at the same time set in motion a timing mechanism, which will automatically close the same at the end of any predetermined interval of exposure.

3. A presser adapted to open the shutters of a photographic camera by forcing air into an expanding-chamber, to keep said shutters open by preventing the return of the air by any suitable mechanism, and at the same time to set in motion a mechanism that will automatically release the air from said chamber at the end of any predetermined interval of exposure, thus allowing the lids to close.

4. The combination of the lever H , pivoted to the frame G in any suitable way, the bracket r' , with its slotted horizontal projection r , the spring-actuated lever s , provided with the notch s^2 , the bulb F , the tube E , and the bulb D , in conjunction with a suitable mechanism for operating the lids or shutters of a photographic camera, substantially as and for the purposes specified.

5. The combination of the spring-actuated nipper-lever i' , the forked bracket j , the spring-actuated hook j' , all attached to the frame G , and the projection u and plate x , secured to the shorter arm of the lever H , all adapted to operate substantially as and for the purposes described.

6. The combination of the presser G H , spring J , the projection r , the lever s , provided with the notch s^2 and bent arm s^3 , and the arm w , attached securely to the shaft k of the clock-work, all adapted to operate substantially as and for the purposes described.

7. The combination of the dial M , the pointer k^6 , the ratchet-wheel k^3 , the pawl k^4 , the gear k^5 , and the spring k' , all adapted to operate substantially as and for the purposes described.

8. The combination of the friction-disk n^2 , mounted upon the shaft n' of the clock-work, the spring-actuated lever o , the bent lever p , and the bent stationary arm p' , all adapted to operate substantially as and for the purposes described.

9. The combination of friction-disk n^2 , mounted upon the shaft n' of the clock-work, the spring-actuated brake-lever o , the bent lever p , the spring-actuated dog q , the arm v , securely fastened to the shaft k , and means for operating the lever p , substantially as and for the purposes specified.

10. The combination of the lids or shutters

5 B B', adapted to close the inner end of the lens-tube of a photographic camera, the shafts *a a'*, the rocker-arms *c c'*, the connecting-rod *d*, and means for operating the same, substantially as and for the purposes specified.

11. The combination of the lids or shutters B B', adapted to close the inner end of the lens-tube of a photographic camera, the shafts *a a'*, the rocker-arms *c c'*, the connecting-rod *d*, and the spring *d'*, all substantially as and for the purposes described.

In testimony whereof we have signed our names to this specification, in the presence of two subscribing witnesses, on this 25th day of August, A. D. 1883.
